UNITED STATES PATENT OFFICE.

JAMES H. McCUALEY, OF CHICAGO, ILLINOIS.

HEATING AND VENTILATING PLANT AND METHOD.

Application filed August 22, 1927. Serial No. 214,482.

It is an object of this invention to provide a method of heating the rooms of dwellings, or of the larger working spaces of stores, warehouses, factories or the like, which consists in returning the air from the heated space from the lower extremities of the room and from below the heated zone of the room to an air heater positioned in the room so that there is a stratum or blanket of air above the working space insulating it from the cold ceiling and thus reducing the area to be heated with an attending marked economy in fuel and absence of draughts along the floor.

Other and further important objects of this invention will be apparent from the disclosures in the specification and the accompanying drawings.

This invention (in a preferred form) is illustrated in the drawings and hereinafter more fully described.

On the drawings:

Figure 1 shows a room in elevation with a heater of the unit type positioned in the centre of the room and a suggested arrangement of air conduits in the floor section.

Figure 2 is a plan view of the above.

As shown in the drawings:

The numeral 10 indicates a heater of the unit type positioned on the floor 17 of the room and midway between the walls 16 of the room.

Heated air is expelled from the heater through the lateral openings as indicated at 15, Figure 1. In a suggested arrangement, the air falling through the space to be heated enters a conduit 12 formed in the floor 17 of the room through an aperture 13 where an upturned end of the conduit 12 registers therein, and is carried along the conduit 12 to emerge through another upturned end 14 which registers in an opening in the floor and within the body of the heater 10.

While the conduit 12 is shown within the floor in Figure 1, it may well be supported below the floor, or consist of a slot formed in the floor with a cover at floor level without interfering with its purpose, namely, to enable the air to be returned to the heater without

the presence of objectionable draughts moving from the walls of the room along the floor 50 and towards the heater and to maintain an undisturbed blanket of insulating air above the working space.

In heating systems employing the unit type of heater positioned on the floor of the room 55 the air is expelled laterally so that the blanket or stratum of relatively cold air above the turbulent zone adjacent to the air discharging openings may remain relatively quiet. This is highly desirable, for this layer insulates the ceiling and reduces the space to be heated by an appreciable amount. The method of the applicant compels the heated air to travel from the discharge openings on the heater outwardly and downwardly towards 60 the walls as indicated at 19 in Figure 1 and decreases its tendency to sweep away the insulating layer. In other words, the turbulent zone adjacent the discharge openings is bent 65 downwardly.

I am aware that many changes may be made, and numerous details of construction may be varied through a wide range without departing from the principles of this invention, and I therefore do not purpose limiting 70 the patent granted hereon, otherwise than necessitated by the prior art.

I claim as my invention:

A heating arrangement for rooms and like spaces having enclosing walls, consisting of 80 a heater disposed therein substantially remote from said walls and having heated air outlets discharging laterally therefrom towards the walls of the room and below the top thereof, and air-return conduits opening 85 at their inner ends into the lower portion of the heater, said conduits having outer intake ends near the said walls and the lower extremities thereof, whereby to avoid draughts along the floor of the room, and to 90 maintain a relatively quiescent stratum of air above the heated zone.

In testimony whereof I have hereunto subscribed my name at Chicago, Cook County, Illinois.

JAMES H. McCUALEY.
